UNITED STATES PATENT OFFICE.

CHARLES A. MADDUX, OF PORTLAND, OREGON.

SPOTLIGHT FOR AUTOMOBILES.

Application filed July 19, 1921. Serial No. 485,905.

To all whom it may concern:

Be it known that I, CHARLES A. MADDUX, a citizen of the United States of America, and resident of Portland, in the county of 5 Multnomah, in the State of Oregon, have invented certain new and useful Improvements in Spotlights for Automobiles, of which the following is a specification, reference being had to the accompanying drawings.

My invention relates to lighting devices for automobiles of the spot light type or that which is adjustable and adapted to be directed at will toward any portion of the 15 road.

The object of my invention, generally stated, is to produce a spot light that is adjustable with customary effect and purpose, and which is also provided with a side light 20 or ray-emitting elongated slot that is adapted to illuminate, on one side, the length of a car to which it is attached, and which is also so disposed as to permit its rotative adjustment in such manner as to direct the 25 rays proceeding from said slot at any angle to one side of the vertical without disturbing the line of direction of the beam of light from the spot light.

What constitutes my invention will be 30 hereinafter specified in detail and succinctly set forth in the appended claims.

In the accompanying drawings,

Figure I is a horizontal, longitudinal section partially in elevation of my invention, 35 and a plan of its support, showing the same in present preferred form of embodiment.

Figure II is a side elevation of the subject matter of Figure I, looking towards the side light.

40 Figure III is a diagrammatic side elevation of a representative form of automobile, showing my spot light attached thereto as in service, and showing the side light thereof deflected downwardly to illuminate the 45 running-board of the car.

Figure IV is a top plan view of the subject matter of Figure III, but showing the side light in substantially horizontal adjustment.

50 Referring to the numerals on the drawings, 1 indicates a spot light case that may be made of metal and of any suitable and preferred design and construction. It is of oblong dimensions and preferably conoidal 55 in shape, tapering from its larger end 2 to-

wards a blunted, preferably rounded, extremity 3.

Within the end 2 of the case, I provide a cup reflector 4 that is covered by a lens 5. Both reflector and lens may be of any usual 60 or preferred design and construction.

Within the wall of the reflector 4 is suitably mounted, in any usual or preferred manner, an electric lamp 7 that is fed by electric wires 8 and 9 insulated within a tube 65 10 that penetrates the case 1 as indicated at 11. Said wires operatively communicate with a suitable source of electric energy, not illustrated.

The apparatus, so far as described, with 70 the exception of the case 1, may be substantially such as that which is comprehended in any ordinary spot light.

In the side of the elongated case 1, substantially opposite the point 11, I provide 75 a reflector 12 that is preferably oblong and whose open side is defined by a frame 15, that may be secured to the wall of the case 1, as by rivets 16. In the bottom of said reflector 12 I provide, preferably, a single 80 electric lamp 17 whose feed wires 18 and 19 are insulated and carried with the wires 8 and 9 within the tube 10. If more than one lamp 17 be used they should be ranged along the longitudinal extent of the frame 15. 85

The frame 15 is provided with a slot-like aperture 20 into which, preferably, fits an oblong lens 21, that is held in place by the said frame.

The aperture 20 is an important functioning element of the side light of my device, and may be made effective irrespective of the shape of the reflector or of the number and arrangement of the lamps behind it. Its function being to restrict to a flat 90 shape the rays of light admitted through it from the lamp 17, for example, it is made in form of a slot, which will produce the desired distribution of rays emitted from the lamp 17 irrespective of the form and disposition thereof.

By reason of the rearwardly inclined disposition of the frame 15 and of the reflector 12, illumination obtained through the aperture 20 is kept directed towards the rear of 10 the car—represented by 23—in all adjustments of the case 1.

For the purpose of effecting all desired adjustments of the case any suitable means may be provided, such, for example, as a 111

universal joint, diagrammatically indicated by the numeral 25, in Figure I, of the drawings.

In operation, the case 1 may be adjusted 5 in the usual manner to direct the rays from the lamp 7 in a forward or oblique direction. By my invention, rays from the lamp 17 or side light may be directed, through 10 rotative adjustment of the case, by aid of the joint 25, so as to illuminate the running board of the car and the road side, or 15 to flash a light horizontally or in an upwardly oblique direction, at desire.

By the aid of my device the side of the 15 car may be illuminated courteously, without glare, for the benefit of the driver of a car moving in the opposite direction; the roadside may be illuminated; the wheels may 20 be illuminated for repairs at night; the running board of a car may be clearly displayed for the benefit of a passenger; signs along the road may be caught; and the side light may be used advantageously in making 25 change from the driver's seat or in securing a plain view of the face of a pedestrian who may be passing, or may hail the driver of the car.

What I claim is:

1. The combination with means of support, 30 of an automobile side lamp comprising a casing provided with openings on front and side, respectively, and means of lighting the same from within, the said side opening being a narrow elongated slot-like 35 aperture, and a cooperating reflector for said side opening adapted to distribute rays of light spreading longitudinally of said aperture but restricted to a flat beam transversely of said aperture, substantially as 40 and for the purpose set forth.

2. The combination with lighting means 45 and a case provided, in operative communication with said means, with a front opening and with a narrow elongated slot-like aperture in its side, of means of support for said case, means for rotative adjustment

of the case upon its support about its axis that is substantially parallel to the said aperture, whereby direction of distribution of the light rays through said side aperture 50 may be varied without disturbing the direction of light distribution from the front opening.

3. The combination with an oblong tapered case provided at one end with an opening, and with an electric lamp and a reflector in operative communication with said opening, of means of support for said case, a frame provided with a narrow, elongated, slot-like aperture mounted longitudinally in 60 the inclined side wall of the case, an electric lamp and a reflector behind said slotted frame, and means of rotative adjustment of the case upon its support, whereby, when the device is mounted upon an automobile, 65 flat rays of light may be constantly directed rearwardly to the side of the car at any desired angle of adjustment in a vertical plane, without disturbance of the direction of light distribution from the end 70 opening in the case.

4. The combination with means of support, 75 of an automobile side lamp comprising a casing provided with a front opening and a side opening, a reflector and lighting means for said front opening, additional lighting means for said side opening, the side opening being a narrow elongated slot-like aperture, and a reflector for said side opening having a contour substantially conforming to the shape of the opening and adapted to project rays of light spreading longitudinally of the opening but restricted to a substantially flat beam transversely of the opening.

In testimony whereof, I have hereunto set my hand in the presence of two subscribing witnesses.

CHARLES A. MADDUX.

Witnesses:

JOSEPH L. ATKINS,
JOHN B. CLELAND.
